CLAIM

The ornamental design for a lid with a loop-shaped handle, as shown and described.

DESCRIPTION

FIG. 1 is an upper perspective view of a lid with a loop-shaped handle, illustrating the lid attached to an exemplary container;

FIG. 2 is an enlarged upper perspective view thereof, with the exemplary container removed for clarity of details;

FIG. 3 is a lower perspective view thereof;

FIG. 4 is a front view thereof;

FIG. 5 is a rear side view thereof;

FIG. 6 is a left side view thereof;

FIG. 7 is a right side view thereof;

FIG. 8 is a top view thereof; and,

FIG. 9 is a bottom view thereof.

(Continued)

The broken lines are shown for the purpose of illustrating environmental subject matter of a container, and parts of the article, none of which form part of the claim.

1 Claim, 9 Drawing Sheets
